FINDING FOR A PIERCED EARRING

Joseph M. Pepitone, North Babylon, N.Y., assignor to
Pelo Industries, Inc., Pawtucket, R.I.

Filed June 2, 1969, Ser. No. 17,457

Term of patent 14 years

Int. Cl. D11—01

U.S. Cl. D45—9

FIG. 1

FIG. 2

FIG. 3

FIG. 4

FIG. 5

FIG. 1 is a side elevation view of a finding for a pierced earring showing my new design;

FIG. 2 is a right side elevational view;

FIG. 3 is a left side elevational view;

FIG. 4 is a top plan view; and

FIG. 5 is a bottom plan view.

I claim:

The ornamental design for a finding for a pierced earring, substantially as shown.
